UNITED STATES PATENT OFFICE.

EDWIN H. LEA, OF RICHMOND, VIRGINIA.

BUCKET.

No. 833,469.

Specification of Letters Patent.

Patented Oct. 16, 1906.

Application filed August 15, 1905; Serial No. 274,327.

To all whom it may concern:

Be it known that I, EDWIN H. LEA, a citizen of the United States, residing at Richmond, in the county of Henrico and State of Virginia, have invented certain new and useful Improvements in Buckets; and I do hereby declare the following to be a full, clear, and exact description of the invention, such as will enable others skilled in the art to which it appertains to make and use the same.

This invention relates to improvements in self-filling attachments for receptacles, and particularly to well or other buckets.

The object of the invention is the provision of means for facilitating the filling of a receptacle with liquids.

Another object of the invention is the provision of means carried by a receptacle, preferably a well-bucket, which will permit the bucket to automatically reverse its position as the same engages the water and is filled.

With these and other objects in view the invention consists of certain other novel constructions, combinations, and arrangements of parts, as will be hereinafter fully described, illustrated in the accompanying drawings, and more particularly pointed out in the claims hereto appended.

In the drawings, Figure 1 is a view in side elevation of a receptacle, preferably a well-bucket, constructed in accordance with the present invention. Fig. 2 is a view in side elevation of a receptacle or bucket which is constructed in accordance with my invention, shown in a position reverse to that illustrated in Fig. 1; the bucket in position for engaging the liquid with its mouth or top downward. Fig. 3 is a perspective view of one of the guides which are secured to the side of the bucket. Fig. 4 is a fragmentary perspective view of the bail, and Fig. 5 is a similar view of another embodiment. Fig. 6 is a fragmentary view in side elevation of the device depicted in Fig. 1. Fig. 7 is a vertical sectional view of another embodiment of the present invention.

Referring to the drawings by numerals, 1 designates a receptacle of any suitable structure, preferably a well-bucket. Secured in diametrically opposite positions upon the sides of the bucket 1 are preferably a pair of guides 2. These guides are secured by any suitable means—as, for instance, staples 3—

to the receptacle, the staples 3 extending through flanges or lips 4, 4 of the guides. 55 Each guide is secured to the bucket at an angle to a vertical plane for facilitating the reversing of the position of the bucket when it engages the water in a well or cistern, or, in fact, any liquid which is of sufficient depth to 60 allow of the operation of the bucket therein.

Each of the guides is preferably formed from a single piece of metal, said guide being provided with an elongated slot 5 and with parallel sides and ends 6 and 7, respectively. The flanges or fastening-lips 4 extend at substantially right angles from the parallel ends 7. Formed at one end of the elongated slot 5 and preferably near the upper end of the guide 2 are notches 8, which are engaged by a longitudinally-movable bail 9, constituting lifting means and through which the bail is inserted before the guards 2 are secured upon the bucket-body 1. 7c

The body portion of the bail 9 may be of 75 any ordinary structure; but I preferably form the ends of the bail with a curved substantially right-angled portion 10, terminating in a comparatively broad or flat downwardly-curved portion 11. The portion 11, 80 which constitutes a shoulder or flange upon the bail, extends at substantially right angles to portion 10 and is proportioned for insertion through the notches 8, as above described. These shoulders or curved portions 85 10 of the bail 9 throw the bail away from the guides 2 and prevent it from rubbing on the sides of the bucket, as well as positively securing the same to the guides 2. It is to be noted that the portions 9 and 11 of the bail, 90 Fig. 6, are approximately parallel, thereby forming a double right angle. In Fig. 5 the bail 9^a is provided with a double button 12, which is also employed in some instances instead of the portion 11 to prevent the bail 95 coming out of the guides after it is positioned within the slotted portions thereof.

In operation the bucket is lowered into the well in the inclined position. (Shown in Fig. 2.) Owing to the positioning of the guides upon the sides of the bucket at an angle to a vertical plane, as soon as the upper portion, Fig. 2, of the bucket engages the liquid the bucket will begin to pivot upon the bail 9 and will consequently place the same 105 in a substantially parallel position with the surface of the liquid; but as the bucket assumes this position the bail will begin to

travel longitudinally within the slots of the guides, and as liquid enters the bucket the same will be submerged in the liquid, and when the bucket is filled the bail will have 5 traveled to the upper end of the guides, Fig. 1.

From practical experience I have found that the foregoing statements are entirely correct and that a bucket when filling has a scoop action. It will always automatically 10 reverse its position by reason of the peculiar positioning of the guides or ears at an angle to a vertical plane, so that the bucket turns from its inverted position, Fig. 2, to its upright position, Fig. 1, when it is being filled 15 with liquid. The bucket may be withdrawn without disturbing the liquid in the reservoir or well to any great extent, which is very desirable in the use of my invention in shallow wells. The notches 8 are of advantage in 20 that when the bucket is being emptied the bail, constituting a handle, will be thereby prevented from sliding freely within the elongated slotted portion of the guides or ears 2, and thereby spilling and slopping the contents by the sudden and unexpected sliding 25 of the bucket, the bucket being retained upon the portions 10 and the notches 8 as pivots until nearly or quite empty. When the bail is in the lower end of the slot, as shown in 30 Fig. 2, it may slide freely during and for filling.

By reason of the peculiar structure of my device the bucket is kept dry and clean. No freezing of liquids therein nor the depositing 35 of foreign substances can occur, as the same is normally in an inverted position, if it is kept hanging in the well, but no matter how slowly the bucket is lowered into the water it automatically reverses its position as it fills 40 and will not disturb the liquid in a well sufficiently to make it muddy.

In Fig. 7 I have shown the receptacle or bucket 1^a provided with longitudinal grooves 13. The guides or ears 2^a are formed from a 45 single piece of material and are provided with elongated slots or apertures 5, similar to the guides 2. Any suitable fastening means— as, for instance, staples 3—may be employed for securing the guides or ears to the receptacle or bucket in the same manner as guides 2 are secured to the receptacle 1. The guides or ears 2^a are therefore flat elongated slotted metallic members constituting plates, which are secured against the side of the receptacle 55 and which have their slots registering with the grooves 13 of the receptacle or bucket. The bail 9 is positioned within the grooves 13 and the slotted portions of the guides 2^a in the same manner as it is secured within the 60 guides or ears 2. Hooks 8^a are secured near the top of the receptacle, so that when the receptacle is filled with liquid and drawn to the top of the well one of the hooks may be caused to engage a horizontal rod for the pur-

pose of dumping the receptacle. The lower 65 flange or lip 4 of each of the brackets is bent at 4^a to form a hook which surrounds a portion of the lower edge of the receptacle or bucket. This hooked structure produces a durable device, as it not only materially assists in securing the bracket to the receptacle, but also clamps the lower hoop upon the receptacle. It is to be noted that, owing to the sending of the receptacle or bucket down into the well in an inverted position, fresh air is 75 taken from the top and delivered at or near the water, and thereby purifying the air in the well.

What I claim is—

1. A device of the character described, 80 comprising a receptacle, guiding means carried by said receptacle, and a bail or handle engaging said guiding means and adapted to travel longitudinally thereof.

2. A device of the character described, 85 comprising a receptacle, guiding means carried by said receptacle at an angle to a vertical plane, and lifting means engaging said guiding means and adapted to travel longitudinally of the guiding means.

3. A device of the character described, 90 comprising a receptacle, guides provided with elongated slots carried by said receptacle, and a movable bail or handle positioned within the slotted portion of said guides.

4. A device of the character described, 95 comprising a receptacle, guides provided with elongated slots carried by said receptacle, at an angle to a vertical plane, and lifting means engaging the slotted portion of said 100 guides.

5. A device of the character described, 105 comprising a receptacle, vertical guides secured to said receptacle, a bail or handle engaging said guides and adapted to travel longitudinally thereof, and means for securing said bail against longitudinal movement upon said guides until the guides are inverted.

6. A device of the character described, 110 comprising a receptacle, guides secured to 115 said receptacle in diametrically opposite positions, each guide provided with an elongated, slotted portion and with notches or detents formed at one end of said slotted portion, and a bail or handle freely movable within the slotted portions of said guides.

7. A device of the character described, 120 comprising a receptacle, guides carried by 125 said receptacle at an angle to a vertical plane, each of said guides formed from a single piece of material, and being provided with an elongated, slotted portion and with parallel sides and ends, apertured lips extending from said ends, fastening means extending through the apertures of said lips and into said receptacle, and lifting means positioned within the slotted portions of said guides.

8. A device of the character described,

comprising a receptacle, guides carried by said receptacle, a bail engaging said guide, said bail provided with an angular end portion, each angular end portion provided with a downwardly-extending broadened end.

9. A device of the character described, comprising a receptacle, guides carried by said receptacle, a bail engaging said guides, said bail provided with ends bent at substantially right angles and terminating in broadened portions.

10. A device of the character described, comprising a receptacle, elongated, slotted guides positioned at an angle upon said receptacle, and lifting means provided with broadened extensions at its ends, positioned within the slotted guides.

11. A device of the character described, comprising a receptacle, elongated, slotted guides carried at an angle upon said receptacle, freely-movable lifting means positioned within the elongated, slotted portion of said guides, and means formed near one end of the slotted portions for preventing movement of said lifting means.

12. The combination with a receptacle, of guides carried by said receptacle, each guide formed from a single piece of material, and being provided with an elongated slot, and

lifting means engaging the slotted portion of 30 said guides.

13. The combination with a receptacle, of a longitudinally-movable bail or handle carried by said receptacle, and means carried by said receptacle for preventing longitudinal 35 movement of said handle while the receptacle is being tilted upon the bail.

14. The combination of a receptacle, of lifting means carried by said receptacle and capable of traveling longitudinally thereof, 40 and means carried by said receptacle near the upper portion thereof for preventing longitudinal movement of said handle until the receptacle is inverted.

15. The combination with a receptacle, of 45 a bodily-movable handle carried by said receptacle and capable of traveling longitudinally thereof.

16. The combination with a receptacle, of guiding means formed at an angle on said receptacle, and longitudinal, movable lifting means engaging said guiding means.

In testimony whereof I affix my signature in presence of two witnesses.
